UNITED STATES PATENT OFFICE.

MAURICE T. BROWN AND GEORGE W. SOUTHERLAND, OF JACKSONVILLE, FLORIDA.

CONDENSER.

1,286,523.

Specification of Letters Patent.

Patented Dec. 3, 1918.

Application filed June 29, 1915, Serial No. 36,962. Renewed January 24, 1918. Serial No. 213,615.

To all whom it may concern:

Be it known that we, MAURICE T. BROWN and GEORGE W. SOUTHERLAND, citizens of the United States, and residents of Jacksonville, in the county of Duval and State of Florida, have invented an Improvement in Condensers, of which the following is a specification.

This invention relates to condensers and 10 more particularly to a condenser adapted for use in connection with apparatus for manufacturing turpentine.

One of the objects of the invention is the provision of a condenser of novel construction which receives the vapor from the still of a turpentine apparatus, condenses said vapor and then discharges the same therefrom.

Another object is to provide a condenser 20 in which there is provided means for effectively retarding the passage of the vapor therethrough and which has a maximum condensing surface, whereby the vapor may be completely condensed.

The inventive idea involved is capable of 25 receiving a variety of mechanical expressions, one of which, for the purpose of illustrating the invention, is shown in the accompanying drawing, in which

Figure 1 is a vertical longitudinal sectional view through the condenser.

Fig. 2, is a fragmentary side elevation thereof, parts being broken away and shown in section.

Fig. 3 is a transverse section on the line 30 3—3 of Fig. 1.

Referring more particularly to the accompanying drawing, in which like reference characters indicate similar parts, the numeral 5 indicates a lower tank preferably 40 of rectangular formation and having an outlet 6 in one end thereof. An upper tank 7 is suitably mounted in the top of the lower tank 5 and has its sides spaced from 45 the sides of said lower tank as indicated at 8 for a purpose which will appear in the course of this description. The bottom 9 of the upper tank 7 is inclined longitudinally, as shown in Fig. 1, and is concave in

cross section, as shown in Fig. 3 in order 50 to facilitate the flow of a fluid therefrom.

The upper tank 7 is provided with a longitudinally extending partition, generally indicated by the numeral 10, which is bent to provide a series of pockets opening alternately in opposite directions, the pockets 11 opening toward the top of the tank while the pockets 12 open toward the bottom thereof. In other words, the pockets on each side of any given pocket open in the same direction. The depth of each succeeding pocket decreases from one end of the tank 7, as 55 illustrated in Fig. 1. The partition 10 divides the tank 7 into upper and lower compartments, the former being adapted to 60 receive cold water from a supply pipe 13 while the latter compartment is connected 65 to the still of a turpentine apparatus (not shown) by means of an inlet pipe 14 which extends through one end of said tank 7 and 70 communicates with the first pocket 12 having the greatest depth. A plurality of baffle plates 15 are arranged transversely of the 75 tank 7 and extend from the bottom thereof a distance into all of the pockets 12 with the exception of the one nearest the inlet pipe 14. These baffle plates 15 coöperate 80 with the pockets 12 formed in the partition to cause the vapor entering the pipe 14 to take a tortuous passage around said plates, 85 as indicated by the arrows in Fig. 1, so that said vapor will be retarded in its movement through the tank and thereby effectively 90 condensed by contact with the walls of said pockets which are rendered cold by the water fed into the upper compartment through the pipe 13. In order to permit 95 drainage of all of the compartments and prevent collection of the condensate therein, the bottom of each plate 15 is provided with a small opening 15'. The lowermost portion 95 of the bottom 9 of the tank 7 is provided with an outlet opening in which is mounted one end of an outlet pipe 16 arranged in the tank 5 and which first extends toward the other end of said tank 95 parallel with the bottom 9 and then is curved to extend in the opposite direction

and has its other end mounted in the end of the tank 5 adjacent to the outlet opening in said bottom 9.

The upper compartment of the tank 7 has 5 arranged transversely thereof, at intervals, plates 17, each of which extends from the top of the tank to a point adjacent the bottom of one of the water pockets 11 thereby permitting water from the pipe 13 to flow 10 under the same into the next succeeding space between said plates. These plates 17 are provided so as to facilitate the removal of water from any one of the compartments formed thereby should said water become 15 too warm to effectively cool the walls of the pockets.

An overflow reservoir 18 is secured to the tank 7 adjacent the top and longitudinally thereof and is provided with a plurality of 20 small openings 19 in its bottom through which the overflow water passes, which enters the reservoir through the small pipes 20. The water flowing through the openings 19 drops into the lower tank 5 through 25 the space 8 between said upper and lower tanks and supplies the latter in order that any vapor which might enter the outlet pipe 16 may be condensed. In order to prevent the water from flowing over the sides of the 30 tank 5 and to maintain the same at a predetermined level in said tank the opening 6 is provided therein.

We claim:—

1. A condenser comprising upper and 35 lower tanks, a partition in said upper tank, means associated with said partition for causing the tortuous passage of a fluid through said upper tank, and an outlet pipe arranged in said lower tank and communicating with said upper tank.

2. A condenser comprising upper and lower tanks, a partition in said upper tank, means associated with said partition for causing the tortuous passage of a fluid 45 through said upper tank, an outlet pipe arranged in said lower tank and communicating with said upper tank, and means carried by the upper tank for transmitting the overflow therefrom to said lower tank.

50 3. A condenser comprising upper and lower tanks, a partition in said upper tank, means associated with said partition for causing the tortuous passage of a fluid through said upper tank, and an outlet pipe 55 having one end connected to an end of said upper tank and extending longitudinally of said lower tank, the other end of said pipe being mounted in the end of the lower tank adjacent the outlet end of the upper tank.

60 4. A condenser comprising a tank having a bottom the longitudinal center of which is lower than its sides, a partition in said tank having pockets opening alternately in opposite directions, and means associated

with certain of said pockets for causing the 65 tortuous passage of a fluid through said tank, said means having openings contiguous to the longitudinal center of said bottom.

5. A condenser comprising a tank, a partition in said tank having pockets opening 70 alternately in opposite directions, said pockets being of decreasing depth from one end of said tank to the other, and means associated with said pockets for causing the tortuous passage of a fluid through said tank. 75

6. A condenser comprising a tank having an inclined bottom, a partition in said tank having pockets opening alternately in opposite directions, and means associated with certain of said pockets for causing the tortuous passage of a fluid through said tank. 80

7. A condenser comprising a tank having an inclined and concaved bottom, a partition in said tank having pockets opening alternately in opposition directions, said pockets 85 being of a decreasing depth from one end of said tank to the other and means associated with certain of said pockets for causing the tortuous passage of a fluid through said tank.

8. A condenser comprising upper and lower tanks, a horizontally arranged partition in said upper tank having pockets opening alternately in opposite directions, means associated with certain of said pockets for 95 causing the tortuous passage of a fluid through said tank, and an outlet pipe for said upper tank mounted in said lower tank.

9. A condenser comprising upper and lower tanks, a horizontally arranged partition in said upper tank having pockets opening alternately in opposite directions, said pockets being of decreasing depth from one end of said tank to the other, means associated with certain of said pockets for causing the tortuous passage of a fluid through 100 said tank, and an outlet pipe for said upper tank mounted in said lower tank. 105

10. A condenser comprising upper and lower tanks, the bottom of said upper tank being inclined, a horizontally arranged partition in said upper tank having pockets opening alternately in opposite directions, said pockets being of a decreasing depth from one end of said tank to the other, means 110 in the lower portion of said upper tank and associated with certain of said pockets for causing the tortuous passage of a fluid through said tank, and an outlet pipe for said upper tank mounted in said lower tank, and plates arranged in the upper portion of said upper tank for dividing the same into compartments. 115

11. A condenser comprising upper and lower tanks, a partition in said upper tank, means associated with said partition for causing the tortuous passage of a fluid 125 through said upper tank, an outlet pipe ar-

- ranged in said lower tank and communicating with said upper tank, and an overflow reservoir carried by said upper tank and adapted to supply said lower tank.
- 5 12. A condenser comprising upper and lower tanks, a horizontally arranged partition in said upper tank having pockets opening alternately in opposite directions, means

associated with certain of said pockets for causing the tortuous passage of a fluid 10 through said tank, an outlet pipe for said upper tank mounted in said lower tank, and an overflow reservoir carried by said upper tank and adapted to supply said lower tank.
